(57) **CLAIM**

The ornamental design for a tire, as shown and described.

DESCRIPTION

FIG. 1 is a front and side perspective view of a tire showing the new design;

FIG. 2 is a front elevation view thereof; and,

FIG. 3 is a side elevation view thereof, wherein the opposite side elevation view appears the same in mirror image.

The broken lines shown in the drawings illustrate portions of the tire that form no part of the claimed design.
